UNITED STATES PATENT OFFICE

104,800

DESIGN FOR A FRUIT JUICER

Eugene Newnham and William H. Fischer, St. Louis, Mo., assignors to Knapp-Monarch Company, St. Louis, Mo., a corporation of Missouri

Application March 2, 1937, Serial No. 67,947

Term of patent 7 years

To all whom it may concern:

Be it known that we, Eugene Newnham and William H. Fischer, both citizens of the United States and residents of the city of St. Louis and State of Missouri, have invented a new, original, and ornamental Design for a Fruit Juicer, of which the following is a specification, reference being had to the accompanying drawing, forming part thereof.

We claim:

The ornamental design for a fruit juicer as shown.

EUGENE NEWNHAM.
WILLIAM H. FISCHER.
